CLAIM

The ornamental design for juicer, as shown and described.

DESCRIPTION

1. Juicer

1.1 is a perspective view showing the juicer of our design;
1.2 is a front elevational view thereof;
1.3 is a rear elevational view thereof;
1.4 is a left side elevational view thereof;
1.5 is a right side elevational view thereof;
1.6 is a top plan view thereof; and
1.7 is a bottom plan view thereof.

The portions of the juicer shown in broken lines are included for the purpose of illustrating unclaimed portions of the juicer and form no part of the claimed design.

1 Claim, 6 Drawing Sheets(56)
